(57) **CLAIM**

The ornamental design for a camera lens adaptor, as shown and described.

DESCRIPTION

FIG. 1 is a top, front and side perspective view of a camera lens adaptor showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view thereof from the left of FIG. 2;

FIG. 7 is a side elevational perspective view from the right of FIG. 2;

FIG. 8 is a top, rear and side perspective view thereof;

FIG. 9 is a view similar to FIG. 1 but with the parts in a different position; and,

FIG. 10 is a top, front and side perspective view thereof when mounted on a camera body.

The parts shown in broken lines are only to illustrate the environment and are not claimed.
